UNITED STATES PATENT OFFICE.

EUGEN REISZ, OF TREPTOW, NEAR BERLIN, GERMANY.

DUPLEX CONNECTION FOR TELEPHONE-RELAYS.

1,322,504.

Specification of Letters Patent. Patented Nov. 18, 1919.

Application filed July 31, 1915. Serial No. 43,016.

To all whom it may concern:

Be it known that I, EUGEN REISZ, a subject of the Emperor of Austria, residing at Treptow, near Berlin, Germany, have invented certain new and useful Improvements in Duplex Connections for Telephone-Relays, of which the following is a specification.

In duplex connections for telephonic trunk line correspondence in which the transmission is effected through telephonic relays, there must exist, as is well known, to intensify the incoming currents, some inductive or other connection between both sides of the trunk and both the primary and the secondary circuits of the relay or relays, to allow of immediate intensification of the transmitter and receiver currents at both sides. In such a connection, however, the magnified currents are apt to react on the relay and to cause the formation of a current therein, which would render the same inoperative, while on the other hand, the differences in the electric properties of the two sides of the trunks, and which are frequently large, would likewise have a disturbing effect on the relay action.

In connections of the kind mentioned, such as hitherto used or proposed, the last-mentioned disturbances of the relay action have been overcome more or less efficiently by the insertion of so-called artificial lines, reproducing as far as possible the electric conditions prevailing in the physical lines, while the first-mentioned difficulties were obviated by the arrangement of duplicated coils, passed in series only by the line currents, but traversed in the opposite direction by the magnified relay currents, so as to avoid any action of the same on the circuit allotted therewith in the latter case. Both methods have also been combined, by connecting one of the said duplicated coils with the physical, and the other with the artificial line. Such constructions, however, possess practical difficulties when in use, resulting from the needless consumption of nearly one-half of the electrical energy in the artificial lines, and from the indispensable constant adjustment of the

same to comply with the constant variation of capacity and resistance, almost continually occurring in a trunk line, with the varying value of insulation, leakage losses, etc.

It is the object of this invention to overcome the above-mentioned difficulties and to obtain a reproduction undisturbed either by the magnified currents or by the different electric properties of the trunk lines on both sides of a relay, without introduction of artificial lines and the drawbacks caused by them.

For this purpose, each trunk running into the exchange, containing the relay or relays, has a separate trunk section in the vicinity of the relay, coupled with the relay circuits on the one side and with the remainder of the trunk on the other side, preferably by the well-known repeater coils. The said section is provided with a third conductor in parallel with the two line wires of the trunk which branches off at the relay side from the exact middle of the repeater coil, in connection with the primary circuit of a relay, and at the other side from the repeater coil in connection with the remainder of the trunk. By these means the two lines constituting one trunk form part of two parallel circuits having a common return conductor, which may be the earth or some separate line or wire, or an existing telegraph or telephone line as the case may be. Moreover, such a section must have a definite length, so that its damping exponent is above a certain value.

I have found that the influence of the inequalities in the electric properties of the trunks upon the relay decreases in proportion as the distance of the sources of said inequalities increases, and if said damping exponent is properly chosen, which means that it may be chosen above a certain value depending upon the length of the trunks, then these inequalities will be of no consequence. The third conductor will allow a connection that excludes every influence of the magnifying currents upon the relay and, at the same time, the high value of the damping exponent will also prevent the inequalities due to the symmetrical connection of the

- third conductor with respect to the repeater coils, or to unequal electric properties in the two branches of said section, to have any marked influence upon the exact compensation caused by subdividing the repeater coil, which is connected with the primary of the relay, into two absolutely equal parts. These unequal parts or elements which may be present in the circuit are, for example, the one-sided connection of the third conductor (the earth), or other electrical differences, even though slight, in the two conductors of the double line such as are made noticeable in long distance lines due to shunts, differences in insulation, and other causes. It is also to be considered that only a correspondingly large part of the long-distance lines connected to both sides of the relay can be of injurious effect on the relay. I have discovered that, as the distance from the relay increases, differences in the characteristics and apparent resistances in the long distance line act injuriously on the relay with diminishing influence. As a result of this discovery, the connection of the third conductor (the earth) as a return line for the intensified currents is not necessarily located at the two end stations themselves but may be located at a predetermined distance from the relay dependent on its sensitivity and intensification, and by using induction coils or transformers, the other two parts of the line to which the telephone devices themselves are connected are pure long distance lines and exclusively double lines. Experience has demonstrated that, even with highly sensitive gas-discharge relays, the distance between them and the transformers with the ground plates, at which normal long distance lines may be connected without affecting injuriously the operation of the relay, may be, for example, 200 kilometers where a 4 millimeter free line is used, this being sufficient to prevent reduction of the sensitivity of the relay.

In such a system it is, moreover, possible to connect the repeater coil, in connection with the secondary of the relay, into said third conductor, preferably near the point where the same is branched off from the middle of the repeater coil in connection with the primary relay circuit, whereby all the above-mentioned advantages will also be secured, since the translation of the magnified currents, as also any reaction of the same upon the relay will be prevented.

If a plurality of relays (especially two relays, one for each direction) be used, the connection is based exactly upon the same principle, the difference residing only in the fact that the coil at the end of the section is in inductive or other connection with the primary circuit of a relay that transmits exclusively to the other side of the trunk, while

the repeater coil, in the third conductor of said section is in inductive or other relation with the secondary circuit of a relay, the primary of which is in connection with the repeater coil at the end of the other side of the trunk.

In the accompanying illustrative drawings Figure 1 represents a diagram showing the connection according to this invention;

Fig. 2 represents a modification for two distinct relays;

Fig. 3 shows a modification of the arrangement according to Fig. 2 with a metallic return conductor;

Fig. 4 represents a second modification of the arrangement according to Fig. 2, and Fig. 5 a third modification thereof.

Referring to these drawings:

In the diagram according to Fig. 1 translators 1, 2 and 12, 13 are connected into the two trunk lines F_1 and F_2 representing any kind of two wire lines. The line currents, which are to be reinforced by the relay, act by means of the windings 3, 4 and 8, 9 upon the winding 5 which is connected into the primary circuit P of the relay. The windings 7 and 11 are connected into the secondary circuit S , that is to say into the circuit containing the currents reinforced by the relay.

The currents flowing into the said windings 7 and 11 serve to induce currents contained in the windings 6 and 10, the said currents flowing across the windings 3, 4 and 8, 9 to the translator coils 2 and 12, while the return to the windings 6 and 10 is effected by aid of a third conductor, *i. e.*, the earth, according to Fig. 1. Provided the damping factor of the portions of the line located between the places where the translators 1, 2 and 12, 13 are erected and the place where the relay is situated be sufficiently large, then the currents flowing in the windings 3, 4 and 8, 9 will prove to be equal for all practical purposes, so that no reaction on the primary circuit of the relay will occur.

By "damping factor" is meant that exponent as a natural logarithm βL which, in telephone lines, shows how great is the decrease in intensity of the voice current in consequence of self-induction, capacity, ohmic resistance and other influences, and which "apparent resistance" acts to reduce the intensity of sound in telephone conversations as the distance of the telephone increases on a logarithmic exponential scale.

If, for example, the current reinforced by the relay attains the tenfold value of the original current, then the damping exponent of each portion of the line situated between the relay and the translators 1, 2 and 3, 4 must be greater than 1. In other

words, with relays which are so sensitive that they intensify the original speaking current ten-fold, it has been found necessary to select a distance between the ground-
5 ed transformer coils 1-2 and 12-13 and the approximately centrally located relay station which will be sufficient that each of these conductor portions shows a weakening in current so that $\beta l = 1$, corresponding
10 to about 200 kilometers of open double line of 4 millimeter copper wire.

The three wire line portion at both sides of the relay must accordingly possess certain definite value of damping dependent
15 upon the degree of reinforcement of the relay, while the impedances of the three wire portion of the line may be chosen independently of one another at both sides of the relay.

20 It will thus be understood that the possibility is given of connecting the one side of the relay to overhead lines and the other side to cable lines without rendering necessary the introduction artificially of the necessary
25 value of damping. In this latter case however these lines must be constructed up to a certain damping factor, as three wire lines.

In order to explain more fully the main advantage of the invention, and which consists in the fact that the whole line is not subject to a complicated modification throughout its whole length or entirely modified by the provision of additional arrangements or apparatus on account of the
30 reinforcement by a relay, but in its main parts is arranged like any normal trunk line, without special reinforcement appliances, the terms "damping exponent" and "characteristic" will hereafter be discussed,
35 and definite examples, with definite values in numbers, will be given.

In every trunk or long distance line on the one hand, owing to the varying currents, the electric and magnetic fields compensate
40 each other, while, on the other hand, the useful power is transmitted to the other end of the line. The current impulse sent over the line has to supply the useful power at the other end of the line, as also the power
45 necessarily spent in consequence of losses occurring during the transmission over the line. These losses may be restricted but cannot be obviated altogether by the inductance distributed all over the line. At each point
50 some of the power transmitted is lost, so that the amount of power arriving at the receiving end is obviously much smaller than that put in at the transmitting end. This law, of course, equally applies to every
55 conductor for continuous current. But the case of continuous current is a somewhat different one, as in the conduction of undulating or wave currents the power supplied at one end has not only to make up

for the losses caused by the resistance and 65 the heating of the conductor, but also for the losses occurring by the transformation of the electric energy in the distant parts of the line. The consumption of electric power in telephone trunk lines is, therefore, 70 governed by another law than the consumption in other lines, and the voltage and current strength (and thereby also the consumption of electric power) decrease according to an exponential curve. Assuming 75 a wave to have traveled a certain distance along the line, the current strength will have decreased at J_0 at the beginning to $\frac{J_0}{\alpha}$ at 80 the end of said distance, α in this case indicating a number larger than 1 (one). At the end of a distance twice as long, the current strength of the wave will only possess a value equal to $\frac{J_0}{\alpha^2}$. Assuming α to have been 85 so chosen that it has reference to 1 (one) km., (equivalent to unit of length), the intensity of the current in a line of l km. will have been reduced to $\frac{J_0}{\alpha^l}$. Now this reduction is termed "space damping" the current intensity. The same law holds true with regard to the tension.

The theoretical development of the problem gives the same result, however, in a different form, there being introduced in the place of the value α , a value of the same physical quality e^β ($e = 2.718 \dots$ being the basis of the natural logarithms), so that 95 $\alpha^l = e^{\beta l}$ and it is this latter mathematical expression for the damping which is commonly used.

The relation existing between the two statements is the obvious and well-known 105 one that $\beta = 2.3 \log^{10} \alpha$. The ratios of current intensities or tensions at the incoming and outgoing ends of a line section of 1 km. at the other end being $1 + \delta : 1$ (δ indicating a definite but very small number), then, in 110 that case, $\alpha = 1 + \delta$ and, therefore, $\beta = 2.3 \log^{10} (1 + \delta)$. However, for the δ values which practically arise, the term $2.3 \log^{10} (1 + \delta)$ proves to be approximately equal to $\delta : f.i.$ $\beta = 2.3 \log (1 + 0.050) = 2.3 \cdot 0.0212 = 0.0487$. Now 115 seeing that β and δ are almost equal, it follows that on a line having a constant β , the current intensity or tension at one end of a line 1 km. in length, will bear a ratio to the current intensity at the other end of the line 120 equal to $1 + \beta : 1$. The value β may be termed the space damping coefficient, and β^l constitutes the damping exponent or damping coefficient for a line l km. in length. For all practical purposes, the indications according to the values β^l are more easy, the numbers being smaller.

In Fig. 2 of the accompanying drawings

there is represented a diagram showing the connections for two distinct relays for the currents arriving from the two sides of the line.

- 5 P_1 and S_1 indicate the terminals leading to the primary and the secondary circuits, respectively, of the first relay, whereas P_2 and S_2 represent the terminals for the corresponding circuits of the second relay.
- 10 The operation of this arrangement is as follows:

The currents coming from the trunk line F_1 act by means of the windings 1, 2 and 3, 4 and 5 upon the primary circuit P_1 of the first relay. The currents reinforced by this relay and coming from the secondary terminals S_1 are transmitted by the windings 10, 11 and further by the windings 12, 13 to the trunk line F_2 . The currents coming 20 from the trunk line F_2 act by means of the windings 13, 12 and 8, 9 and 5' on the primary circuit P_2 of the second relay and the currents reinforced by this latter are transmitted by the windings 7, 6 and further by 25 the windings 2, 1 to the trunk line F_1 .

In the case of this arrangement the currents are transmitted in a reinforced state from the one trunk line to the other without giving rise to any reflection.

- 30 The degree of reinforcement obtained by means of the arrangement according to Fig. 2 is consequently much greater than that obtained by means of the arrangement shown in Fig. 1, since in this latter case the currents, coming from one trunk line are transmitted to the other trunk line by means of the relays, are reflected to an increased degree along the line after passing the transmitting station, this reflection entailing a 40 reduction in the degree of reinforcement.

The arrangement shown in Fig. 3 is identical to that represented in Fig. 2 with the sole difference that instead of the earth there is employed a metallic return conductor, say for example telegraph lines F_3 and F_4 , respectively, running alongside of the trunk lines.

- In Fig. 4 there is shown an arrangement in the case of which neighboring telephone 50 lines are made use of for the purpose of effecting the return of the currents reinforced by the relay. Between the said telephone lines F_3 and F_4 of the type commonly in use and which run alongside of the lines 55 F_1 and F_2 , there are interconnected the bridge coils D_1 to D_4 . The coils D_2 and D_3 are located as closely as possible to the place where the relay is situated, while the coils D_1 and D_4 are situated as near as possible to 60 the place where the translator coils 1, 2 and 12, 13 are connected into the circuit.

The currents reinforced by the relay and which are transmitted in the manner above set forth to the trunk lines F_1 and F_2 have

no influence whatsoever upon the lines F_3 , 65 and F_4 for the simple reason that the speaking currents do not give rise to any difference in voltage between the two conductors F_3 and F_4 .

In the arrangement according to Fig. 5 70 there are connected into two pairs of two wire lines F_1 to F_4 two relays, one for each pair provided with the primary circuits P_1 to P_4 and the secondary circuits S_1 to S_4 . In addition hereto there are arranged eight 75 bridge coils D_1 to D_8 . In the case of this said arrangement no such auxiliary lines are required as are mentioned with reference to the arrangements according to Figs. 1 to 4. The two strands of a two wire line constitute 80 the return conductors for the reinforced currents of the other two wire line in every direction.

The manner in which this arrangement is intended to operate is the same as that according to Fig. 4.

The places where the coils 1, 2 and 12, 13 are connected into the circuit must be at such a distance from the relay, or the relays, as to prevent any further influencing of the 90 partial current in the windings 3, 4 and 8, 9 in consequence of a connection having been established with the trunk lines F_1 and F_2 . This will render it impossible for the coils 1, 2 and 12, 13 to be connected into the circuit 95 at the exchange where the relay, or the relays, are located.

The interconnection of artificial lines between the coils 1, 2 3, 4 8, 9 and 12, 13 (by which means the possibility would be given 100 of effecting the connection into the circuit at the exchange) does not appear to be advantageous, since this would be attended by a considerable reduction of the degree of reinforcement of the relay.

What I claim is:

1. In combination with a telephone repeater system comprising double line trunks and a telephone relay between said trunks having a primary and a secondary circuit, 110 a separate trunk section at each side of the relay electrically coupled with the remainder of the trunk and with the relay circuits, the length of said section being above a definite minimum length, corresponding to 115 a damping exponent of a magnitude sufficient to practically annihilate the effect of the inequalities in the electric properties of the trunk lines on both sides of the relay.

2. In a telephone repeater system comprising double line trunks and a telephone relay between said trunks having a primary exciting and a secondary transmitting circuit, the combination of a separate trunk section 120 at each side of the relay with repeater coils 125 to electrically couple the same with the remainder of the trunk and with the relay circuits, and a third conductor in said sec-

- tion in parallel to the trunk lines of the same branched off from the exact middle of the repeater coil at the relay side and from some point of the repeater coil at the opposite side so as to transform said section into two parallel circuits including the two lines of the trunk and having a common return conductor, the said section having a definite minimum length corresponding to a damping exponent of sufficient magnitude to practically annihilate the effects of the inequalities in the electric properties of the two circuits connected in parallel. 65
3. In a telephone repeater system comprising a double line trunk and a telephone relay between said trunks having a primary exciting and a secondary transmitting circuit, the combination of a separate trunk section at each side of the relay provided with repeater coils, one of said coils coupling said section with the remainder of the trunk and another coupling the same with the primary circuit of the relay, and a third conductor in said section in parallel with the two trunk lines branched off from the exact middle of the repeater coil coupled with the primary relay circuits and from some point of the repeater coil coupled with the remainder of the trunk, the repeater coil in inductive relation with the secondary circuit being arranged in said third conductor near the branching point at the relay side of said third conductor. 70
4. In a telephone repeater system having double trunk lines and a relay connected with each of said trunk lines to transmit the telephonic conversation from one trunk line to the other, each of said relays having an exciting primary circuit and a transmitting secondary circuit, the combination of separate trunk line sections at each side of the relay provided with repeater coils, one of said repeater coils being in inductive relation with a corresponding coil at the end of the remainder of the trunk, another coil being coupled with the primary circuit of the relay, the secondary circuit of which is coupled with the other trunk line, a third conductor in said section branched off from the middle of the last-mentioned coil and from the end of the first-mentioned repeater coil at the off side of the section, thus transforming said section into two parallel circuits having a common return conductor, and a third repeater coil inserted in said additional conductor of the section, said coil being in inductive relation with the secondary circuit of the relay, the primary of which is coupled with the repeater coil of the other trunk, the separate sections of the trunk adjacent the relays being of such length that their damping exponent is of sufficient magnitude to overcome the effects due to difference in the electric qualities of the trunks or of the parallel circuits in each section so as to obtain a practically equal flow of current in the two parts of each repeater coil coupled with the primary of the associated relay. 75
5. In a telephone repeater system having double trunk lines and a relay connected with each of said trunk lines to transmit the telephonic conversation from one trunk line to the other, each of said relays having an exciting primary circuit and a transmitting secondary circuit, the combination of separate trunk line sections at each side of the relay provided with repeater coils, one of said repeater coils being in inductive relation with a corresponding coil at the end of the remainder of the trunk and with the relay circuits, a double trunk line running for the extent of said section in parallel with the other trunk lines, and means to connect said second trunk line with the exact middle of the repeater coil at the relay side of the section and with the end of the repeater coil at the opposite side so as to transform the same into a third return conductor connected in parallel with the two lines of the trunk section, the said section having a definite length corresponding to a damping exponent of sufficient magnitude to practically annihilate the effects due to difference in the electric qualities of the trunks or of the parallel circuits formed in each section by the interposition of the return conductor. 80
6. In a telephone repeater system having double trunk lines, a relay connected with each of said trunk lines to transmit the telephonic conversation from one trunk line to the other, each of said relays having an exciting primary circuit and transmitting secondary circuit, the combination of separate trunk line sections at each side of the relay provided with repeater coils, one of said repeater coils being in inductive relation with a corresponding coil at the end of the remainder of the trunk and with the relay circuits, a double trunk line running for the extent of said section in parallel with the other trunk lines, and bridging resistance coils in said second trunk line, one of said coils being situated as near as possible to the repeater coil connected with the primary relay circuit, the other coil being situated as near as possible to the repeater coil at the off side of the section, the first bridging coil having its middle connected with the exact middle of the repeater coil at the relay side, the other bridging coil having its middle connected to the end of the repeater coil at the distant side of the section, both of the second trunk lines thus forming a third conductor in said trunk section, transforming the same into two parallel circuits having a common return conductor, the separate trunk line section hav- 85
- 100
